UNITED STATES PATENT OFFICE.

ALTON F. TOWLE, OF COLORADO SPRINGS, COLORADO.

ENGINE.

No. 889,991.

Specification of Letters Patent.

Patented June 9, 1908.

Application filed May 29, 1907. Serial No. 376,400.

To all whom it may concern:

Be it known that I, ALTON F. TOWLE, a citizen of the United States, residing at Colorado Springs, in the county of El Paso and State of Colorado, have invented certain new and useful Improvements in Engines, of which the following is a specification.

This invention relates to improvements in that type of engine, wherein the cylinder and the piston containing it are both reciprocated in order to derive power from the pressure of motive fluid against the cylinder heads.

A primary object of the present invention is to provide novel means of a simple nature, whereby the steam or other motive fluid is admitted to the movable cylinder without the necessity of flexible couplings, swinging pipes and the like, and the cylinder is inclosed so that the full effect of the steam is secured and condensation avoided.

A further and important object is to improve the engine in certain details of construction so that the same is more practical and effective.

The preferred embodiment of the invention is illustrated in the accompanying drawings, wherein:

Figure 1 is a top plan view of the same. Fig. 2 is a side elevation. Fig. 3 is a longitudinal sectional view. Fig. 4 is a cross sectional view. Fig. 5 is a horizontal sectional view.

Similar reference numerals designate corresponding parts in all the figures of the drawings.

In the embodiment illustrated, a stationary casing 6 is employed that constitutes in effect a steam chest, and has a motive fluid supply pipe 7 connected thereto. An exhaust pipe 8 is also connected to the casing, preferably at the central portion thereof. Within the casing is mounted a reciprocating cylinder comprising a body 9, in the ends of which are threaded rings 10. Heads 11 are bolted, as shown at 12 to said rings. The cylinder slides upon a lower bearing strip 13, and has outstanding guides 14 on its opposite sides that operate in guideways 15 formed upon the diametrically opposite inner sides of the casing or steam chest. The cylinder, as shown in Fig. 4 is of less diameter than the bore of the casing or steam chest, and consequently the steam or motive fluid can pass freely around it.

A reciprocating piston 16 is mounted in the cylinder, and a piston rod 17, connected thereto, projects through a suitable stuffing box 18 in one head of the cylinder and through another stuffing box 19 in the casing head, said rod being connected to a suitable cross head 20. The cylinder has also connected thereto cylinder rods 21 that slide through stuffing boxes 22 in the casing head, and are connected to another cross head 23. An engine shaft 24 is provided with oppositely disposed cranks 25, and pitmen 26, connected to said cranks, have suitable connections with the cross heads 20 and 23.

The cylinder is provided at its ends with ports 27 that communicate with the interior of the casing or steam chest in which said cylinder is located. This communication is controlled by a valve. While any suitable valve mechanism may be employed, in the particular embodiment illustrated, a sliding valve 28 is provided that is interposed between the adjacent walls of the cylinder and casing and has a channel 29 communicating with the exhaust 8. The channel has its ends 30 opening through the under side of the valve so as to alternately communicate with the ports. Thus when one port is in communication with the interior of the casing or steam chest, the other will be in communication with the channel 29, and consequently with the exhaust 8.

Any desired mechanism may be employed for operating the valve. In the present embodiment, said valve has a stem 31 slidably mounted in a bearing 32 carried by the cross head 23, and having a link connection 33 with a lever 34. The fulcrum of this lever has a link connection 35 with an eccentric 36 mounted on the engine shaft 24, while the opposite end of said lever has a link connection 37 with a depending arm 38 carried by the cross head 20. Vents 39 are preferably located in the lower portions of the cylinder heads, and are controlled by outwardly opening valves 40, said valves being preferably located in suitable cages 41.

In the operation of the engine, steam or other motive fluid is admitted to the casing or steam chest 6 through the pipe 7, and consequently will practically surround the cylinder. There will thus be very little condensation of the steam, and said steam or motive fluid entering one end of the cylinder will drive the piston in one direction and the cyl-

inder in the opposite direction. When the end of the stroke is reached, the valve shifts in a manner well understood, thus exhausting the steam or motive fluid before admitted, 5 while admitting steam or motive fluid to the other end of the cylinder and effecting a reversal of movement of the cylinder and piston. It will thus be seen that the full force of the steam is secured, inasmuch as both the 10 cylinder and piston are operating to drive the engine shaft, and no swinging pipes or flexible couplings are employed. Consequently condensation is materially reduced. At the same time, if through any cause the pressure 15 in the casing or steam chest falls below that in the cylinder, or if water does accumulate in said cylinder, the valves 40 will automatically open, thus relieving the pressure or permitting the escape of the water.

20 From the foregoing, it is thought that the construction, operation and many advantages of the herein described invention will be apparent to those skilled in the art, without further description, and it will be understood 25 that various changes in the size, shape, proportion, and minor details of construction, may be resorted to without departing from the spirit or sacrificing any of the advantages of the invention.

30 Having thus fully described my invention, what I claim as new, and desire to secure by Letters Patent, is:—

1. In an engine of the character set forth, the combination with a casing member for 35 motive fluid, of a reciprocatory cylinder member located in the casing member, an oppositely movable reciprocatory piston member located in the cylinder member, means connecting the cylinder and piston members 40 to effect their opposite movements, and means for admitting motive fluid from the casing member into the cylinder member to cause the opposite movements of said cylinder and piston members.

45 2. In an engine of the character set forth, the combination with a casing member for motive fluid, of a reciprocatory cylinder member located in the casing member and permitting the motive fluid to flow freely past it to 50 both ends of the casing member, an oppositely movable reciprocatory piston member located in the cylinder member, means for admitting motive fluid into the cylinder member, and valve mechanism controlling said 55 admission.

60 3. In an engine of the character set forth, the combination with a casing member for motive fluid, of means for admitting motive fluid into the casing member, a reciprocatory cylinder member located in the casing member, a reciprocatory piston member located in the cylinder member, means for admitting motive fluid from the casing member into the cylinder member, and valve mechanism controlling such admission, said valve mechan-

ism being located in the casing member between adjacent portions of the casing and cylinder walls.

4. In an engine of the character set forth, the combination with a stationary steam chest, of a reciprocatory cylinder located therein and of less cross sectional area than the same, said cylinder having ports at its ends that communicate with the interior of the steam chest, a reciprocatory piston located in the cylinder, means for supplying motive fluid to the steam chest, and valve mechanism located in the chest and controlling the ports of the cylinder.

5. In an engine of the character set forth, the combination with a stationary casing constituting a steam chest, of means for admitting motive fluid to said steam chest, a reciprocatory cylinder located in the casing or chest, and of less diameter than the same, 80 said cylinder having ports at its ends that communicate with the interior of the casing or chest a reciprocatory piston located in the cylinder, valve mechanism located in the casing or chest and interposed between the same and the cylinder for controlling the cylinder ports, an engine shaft having oppositely disposed cranks, piston and cylinder rods connected respectively to the piston and cylinder, said rods projecting from the casing or 85 steam chest and having connections with the cranks, and actuating means for the valve mechanism.

6. In an engine of the character set forth, the combination with a stationary casing, of means for admitting motive fluid thereto and exhausting it therefrom, a reciprocatory cylinder located in the casing and having ports that communicate with the interior of said casing, a piston located in the cylinder, a 100 valve located in the casing and interposed between the same and the cylinder, said valve controlling the ports of the cylinder and having a channel arranged to aline alternately with said ports, said channel communicating 105 with the exhaust.

7. In an engine of the character set forth, the combination with a stationary casing having opposite guiding means, of a reciprocatory cylinder located therein and having 110 guides that engage the guiding means, an oppositely moving piston located in the cylinder, means for effecting the opposite movements of the cylinder and piston, means for supplying motive fluid to the casing, means located within the casing for admitting the motive fluid from said casing into the cylinder, and means for exhausting the motive 115 fluid from the cylinder.

8. In an engine of the character set forth, the combination with a casing comprising a steam chest, of means for supplying motive fluid to the steam chest, a cylinder slidably mounted in the steam chest and having portions spaced therefrom to permit the motive 120 fluid to escape.

fluid to flow freely from end to end of the casing, means for admitting motive fluid from the steam chest into the cylinder, an oppositely operating piston, and means connected to the piston and cylinder for effecting their opposite movements.

9. In an engine of the character set forth, the combination with a casing, of a cylinder slidably mounted therein and comprising a body, rings fitted into the ends of the body, and heads detachably secured to the rings, a piston slidably mounted in the cylinder, means for admitting motive fluid to the casing and cylinder and exhausting it from said cylinder, and means connected to the piston and cylinder for effecting their opposite movements.

10. In an engine of the character set forth, the combination with a stationary casing constituting a steam chest and having opposite guides, of a cylinder slidably mounted in the casing and of less diameter than the same, said cylinder being slidably mounted on the guides and having ports at its ends that communicate with the interior of the casing, means for admitting motive fluid to the casing, means for controlling the passage of motive fluid from the casing into the cylinder, an exhaust from said cylinder, a pis-

ton reciprocating in the cylinder, piston and cylinder rods connected respectively to the piston and cylinder and slidably extending through one end of the casing, an engine shaft having oppositely disposed cranks, and connections between the rods and cranks.

11. In an engine of the character set forth, the combination with a casing, of a reciprocating cylinder operating therein, means for admitting motive fluid to the casing, said means, casing and cylinder being so arranged that the motive fluid pressure is simultaneously equal at both ends of the cylinder, a reciprocating piston operating in the cylinder, means connected to the cylinder and piston for effecting their opposite movements, and means for alternately admitting motive fluid to the cylinder on opposite sides of the piston to effect the simultaneous movements of the piston and cylinder in opposite directions.

In testimony whereof I have signed my name to this specification in the presence of two subscribing witnesses.
